UNITED STATES PATENT OFFICE.

JOSEPH H. McEVOY, OF DALLAS, TEXAS.

SHEET-METAL ROOF-JOINT.

SPECIFICATION forming part of Letters Patent No. 749,943, dated January 19, 1904.

Application filed May 29, 1903. Serial No. 159,296. (No model.)

To all whom it may concern:

Be it known that I, JOSEPH H. McEVOY, a citizen of the United States, residing at Dallas, in the county of Dallas, State of Texas, have 5 invented certain new and useful Improvements in Sheet-Metal Roof-Joints, of which the following is a specification, reference being had therein to the accompanying drawings.

This invention relates to a sheet-metal roof- 10 joint, and particularly to an underlying and overlapping joint between adjacent sheets of roofing material.

The invention has for an object to provide 15 a roofing-sheet having at its edges parallel ridges separated by flat securing portions, the ridges upon the opposite edges of each sheet being of different diameter transversely, so as to overlap or seat upon each other, while the body of the sheet is provided with an expansion- 20 ridge to prevent any loosening of the joint by expansion or contraction.

Other and further objects and advantages 25 will be hereinafter set forth, and the novel features of the invention defined by the appended claims.

In the drawings, Figure 1 is a perspective 30 of the invention, showing adjacent ridges in position for assembling. Fig. 2 is a vertical cross-section of the parts when assembled. Fig. 3 is a similar view showing the parallel 35 ridges bent away from the expansion-ridge to form the locking-joint. Fig. 4 is a modified form of the invention in which the locking-ridges are bent toward the expansion-ridge. Fig. 5 is a vertical section of the modified 40 form of the invention wherein the expansion-ridge is disposed in the body of the sheet, while the locking-ridges are shown at the left in their assembled position and at the right in their interlocking position; and Fig. 6 is a vertical cross-section of a car-roof, 45 showing the application of the roofing-sheet thereto.

Like letters of reference refer to like parts 50 in the several figures of the drawings.

The letter A designates a roofing-sheet of any desired size, preferably of greater length than width, so as to extend continuously across the roof of a car A', as shown in Fig. 6, and 55 permit the ends of the sheet A² to be bent

downward and secured to the sides of the car. These sheets are preferably about ten feet in length and thirty inches in width. Upon the opposite longitudinal edges of each sheet the locking-ridges B are provided, and those upon one edge being of greater transverse diameter than upon the other, so as to permit the uppermost sheet to overlap the ridges upon the underlying sheet. Between these ridges the flat securing portion B' is provided through 60 which a nail or other securing means may be passed, as shown in Figs. 2 and 3, for the purpose of securing the sheet to the roof-timber. Each of these sheets is also provided with an expansion-ridge extending parallel to the locking-ridges. For instance, as 65 shown in Fig. 1, the expansion-ridge may be located between the locking-ridges at each edge of the sheet. When this expansion-ridge is located at the point between the locking-ridges, it also performs an important function of preventing the entrance of water through the 70 seam, even if the roof be flooded, as it would be necessary for the water on the roof to rise and continue above the top of this ridge before 75 any could leak or work its way through the joint. When the roofing-sheets are applied, one longitudinal edge of each sheet is secured to the foundation or the roofing-timber A³, as shown in Fig. 2, while the ridges upon the 80 opposite edge of this sheet are seated upon the corresponding ridges of the previously-secured sheet extending parallel beneath the same. The locking-ridges are then bent downward upon the sheet to form a tight interlocking 85 joint by means of which the free end of the sheet just applied is secured to the sheet previously fixed to the roof. This securing may be effected by bending the locking-ridges away from the expansion-ridge, which is always left standing, as shown in Fig. 3, or bending toward the expansion-ridge, as shown 90 in Fig. 4, in which latter position they tend to support and strengthen the expansion-ridge. 95

In the modified form of the invention which is shown in Fig. 5 the parallel locking-ridges B³ extend at opposite longitudinal edges of the sheet and are secured, as before described, by bending downward, as shown at the right 100

of said figure, while the expansion-ridge B⁴ is disposed centrally of the sheet in order to permit the expansion and contraction to which the sheet is subjected in its exposed position 5 owing to the extreme changes in temperature to which the car-roof is exposed in the travel of the car from point to point.

This invention is adapted for any use, but is particularly adapted for the roofs of box 10 or other railway cars upon which it is essential to provide a thoroughly water-tight joint which will not be loosened by the expansion and contraction of the metal of the roof and which may be extended continuously from 15 one side of the car to the other. Owing to the presence of brakemen upon the roof of the car it is also essential that the joint be thoroughly interlocked and bent down upon the top of the sheet, so that it cannot be injured 20 by the pressure incident to walking thereon and while the water-tight seam must be secured, which would prevent the entrance of moisture in the movement of the car which causes the rain to impinge laterally against 25 the joint. The presence of the expansion-ridge between the locking-ridges prevents the pulling apart of the seams and the buckling of the sheets, while it also prevents the entrance of water over or around the locking-ridges if the latter become injured or are not 30

thoroughly sealed by being bent downward upon the body of the sheet.

Having described my invention and set forth its merits, what I claim, and desire to secure by Letters Patent, is—

35

1. A sheet-metal roofing-joint comprising a sheet having at one edge vertically-disposed parallel ridges separated by a flat securing portion, and an overlapping sheet having at one edge parallel ridges separated by a flat 40 covering portion and seated upon the underlying ridges said ridges being bent downward into a horizontal plane upon the top of the overlapping sheet.

2. A sheet-metal roofing-joint comprising 45 a sheet having at one edge parallel ridges separated by flat securing portions, and an overlapping sheet having corresponding ridges seated upon the underlying ridges and bent downward upon the top of the sheet, and a 50 standing expansion-ridge between the edge ridges upon the underlying and overlapping sheets.

In testimony whereof I affix my signature in presence of two witnesses.

JOSEPH H. McEVOY.
